A. E. HUDSON

FASTENER SETTING MACHINE

Filed Aug. 16, 1920

UNITED STATES PATENT OFFICE.

ALBERT E. HUDSON, OF BEVERLY, MASSACHUSETTS, ASSIGNOR TO UNITED SHOE MACHINERY CORPORATION, OF PATERSON, NEW JERSEY, A CORPORATION OF NEW JERSEY.

FASTENER-SETTING MACHINE.

Application filed August 16, 1920. Serial No. 403,674.

To all whom it may concern:

Be it known that I, ALBERT E. HUDSON, a citizen of the United States, residing at Beverly, in the county of Essex and State of 5 Massachusetts, have invented certain Improvements in Fastener-Setting Machines, of which the following description, in connection with the accompanying drawings, is a specification, like reference characters on 10 the drawings indicating like parts in the several figures.

This invention relates to machines for setting fasteners, and more particularly to machines of the type in which the work is fed 15 automatically step by step. In those machines that feed the work the feeding mechanism is usually organized so that it may be regulated to vary the length of the feeding steps and consequently the distance between 20 successive fasteners, but excepting in machines for special purposes a change in the regulation can only be made manually. Nevertheless it is desirable for some special kinds of work to vary the spacing of the 25 fasteners automatically. This has been done heretofore by machines organized to set a series of fasteners at gradually increasing or decreasing intervals, but not otherwise.

A demand has recently arisen for a fastener-setting machine capable of using long 30 and short feeding steps alternately, such demand coming from manufacturers of brassières, but heretofore no machine has been organized to meet this demand. Accordingly 35 an object of the present invention is to provide a fastener-setting machine comprising regulatable work-feeding mechanism and automatic means for regulating said mechanism so as to produce two lengths of 40 feeding steps alternately.

Another object of the invention is to provide for varying the length of one or both feeding steps to meet varying conditions. This may be done, according to the present 45 invention, so as to produce any one of three different results, to wit, varying the length of the longer or the shorter step without varying the length of the other step, varying the length of both steps without varying 50 the difference between their respective lengths, or varying the length of both steps and also varying the difference between their respective lengths. A feature of the invention, therefore, consists in automatic mech-

anism capable of being adjusted and regulated so as to meet the aforesaid fundamental requirement and also to afford a variety of results as to the intervals between the fasteners. 55

The invention consists further in improved features of construction by which the desired variations in spacing may be brought about. A machine embodying the invention is hereinafter described and is illustrated by the accompanying drawings, in which— 60

Fig. 1 is a perspective view partly in section, the fastener-supplying mechanism being omitted for the sake of clearness;

Fig. 2 is a front elevation partly in section including a work-support, an article of 70 work thereon, and the work-feeding and fastener-setting instrumentalities in the act of clenching a fastener;

Fig. 3 is a view similar to Fig. 2 showing the work as having been fed a relatively 75 short distance from the first position and the setting tools as having set another fastener at a corresponding distance from the first fastener;

Fig. 4 is a view similar to Figs. 2 and 3 80 excepting that the work is shown as having executed a second feeding step longer than the first, the setting tools being in the act of setting a third fastener at a relatively great distance from the second fastener; 85

Fig. 5 is a perspective view of a fragment of work in which a series of fasteners are set according to the evolution represented by Figs. 2, 3 and 4, that is, with alternate long 90 and short intervals between successive fasteners; and

Fig. 6 is a detail of construction including adjustable and resilient connections by which the feeding mechanism is regulated 95 automatically.

The invention is illustrated as embodied in a machine of the same general type as that illustrated and described in United States Letters Patent 603,023, granted April 26, 1898 on an application of Seymour Field, and since the said patent will be sufficient to show certain parts of the machine not completely described herein, no attempt has been made to provide a complete showing of the machine on the accompanying drawings. 100

The machine frame 10 is provided with a table or work-support 11 along which the work is fed automatically as the fasteners 105

are inserted and clenched. For the particular purpose hereinbefore mentioned, that is, the manufacture of brassières, a channel-shaped guide 12 is fastened on the work-support so as to provide a throat 13 through which a strip 14 (Fig. 6) comprising superposed layers of sheet material such as fabric may pass. This guide is clamped to the work-support by screws 15 and is formed so as to provide for adjustment transversely of the direction of feeding movement. In the present instance the work is fed from right to left.

In the manufacture of brassières two companion rows of eyelets are provided to receive laces by which the garment may be tightened about the body as in a corset, and accordingly the machine chosen for illustrating the invention is provided with eyelet-setting mechanism including an eyelet-inserting tool 16 and a clenching tool 17. Although these tools and other parts of the machine, excepting the automatic regulating mechanism hereinafter described, embody well-known construction the general organization will be described. The inserting tool 16 is carried by a vertically movable plunger 18 and is operated by a cam 19 carried by a shaft 20. The cam cooperates with a roll 21 carried by the plunger. Although the drawings do not illustrate any means for supplying eyelets it may be understood that a raceway is provided for that purpose and that it is operated in a well-known manner to deliver the eyelets to the tool 16 below the work table, and that this tool carries the eyelet upwardly and inserts it into a hole previously punched in the work. The eyelet-receiving holes are formed by a punch 22 and punch-block 23 which stand at one side of the clenching locality and are shifted laterally away from said locality after each punching operation so as to enable the pilot 24 of the clenching tool to enter the punched hole preparatory to feeding the work to the next eyelet-receiving position. The punch is carried by a lever 25 the fulcrum pin of which is indicated at 26. The punch is moved up and down by a cam 27 through the agency of suitable connections including a vertically movable yoke 28 and a swiveled cross-bar 29 carried thereby and extending through a horizontal opening 30 in the punch lever. These connections enable the punch lever to swing horizontally relatively to the bar 29 as formerly. The punch-block and the pivot member 26 are both carried by a substantially horizontal bar 31 which, as formerly, is arranged to turn about a vertical axis substantially midway between the punch-block and said pivot so as to provide for lateral movement of the punch and punch-block. Fig. 2 shows the punch and punch-block spaced from but relatively close to the clenching locality and about to form

a new hole in the work preparatory to a relatively short feeding step. Fig. 3, however, shows the punch and punch-block further to the right and about to form a hole at a relatively great distance from the punching locality preparatory to a relatively long feeding step. The punch and punch-block are automatically shifted back and forth from the position shown by Fig. 2 to that shown by Fig. 3 so as to form the holes alternately at a relatively short and a relatively long distance from the eyelet being clenched, the shifting of the punching devices to either one of said positions occurring in each alternate cycle of the setting mechanism.

The clenching tool 17 is carried, as formerly, by a lever 32 the fulcrum of which is horizontal and is partly shown at 33 in Fig. 1. This lever is mounted in a frame 34 having a vertical stem (not shown) bearing in the frame 10 and constituting the fulcrum about which the punch and punch-block are turned as hereinbefore explained. For a more complete showing see the aforesaid Patent 603,023. The up and down motions of the clenching tool are received from a cam (not shown) at the rear end of the shaft 20, said cam serving to reciprocate a vertical plunger 35 having an open rectangular head 36 at its upper end. The rear end of the punch lever 32 extends into this head and is operatively connected thereto by suitable ball-and-socket connections indicated as a whole at 37. These connections are capable of swinging laterally in the head 36 while maintaining positive operating connection between the head and the lever at all times in well-known manner.

Before describing the details of the automatic mechanism by which the long and short feeding steps are produced alternately a brief explanation of the operation of the machine as thus far described will facilitate an understanding. While the setting tools are clenching an eyelet, as shown by Fig. 2, the punch descends to the punch-block, thereby forming the next eyelet-receiving hole. The punch is then immediately lifted out of the work and is shifted to the right so as to enable the clenching tool to take its place preparatory to feeding the work. A presser foot (not shown) bears at this time on the work to prevent it from slipping, and the setting tools are retracted from each other, the lower tool to take another eyelet from the raceway and the upper tool to move to its preliminary position for feeding. The upper tool therefore moves to the right until it is in registration with the previously punched hole and then descends so as to insert its pilot 24 through the hole. The upper tool then moves from right to left, thereby feeding the work and coming to rest when it is again in registration with the lower tool. The two setting tools then

cooperate to set the next fastener, and while so doing the punch takes a new position preparatory to punching the next hole.

The mechanism for moving the lever 32 laterally to feed the work is also similar to that shown and described in the aforesaid patent, and comprises a grooved cam 38, an arm 39 cooperating therewith, a vertical rockshaft 40 connecting the arm 39 with an arm 41, a link 42, and a horizontally movable member 43 arranged to swing about the plunger 35 and connected to the link so as to be oscillated thereby. A block 44 is adjustably arranged in a radial slot 15 formed in the member 43 and carries a superposed plate 45 with which it is connected by a pivot member 46. The plate 45 has tongue-and-slot connection with the feed frame 34 in such manner that the amplitude 20 of feeding motion may be increased by shifting the pivot 46 toward the front of the machine and decreased by shifting it toward the rear. The plate 45 is provided with a curved slot 47 which is occupied by 25 a sliding block 48, the latter having swiveled connection with the rear end of the bar 31 by which the punch is shifted laterally.

A feed-regulator or controller 50 is arranged to swing about the plunger 35 to increase and decrease the length of the feeding step, the operating connection between this controller and the sliding block 44 being provided by a link 51. The regulator 50 plays over a stationary plate 52 having 30 any desired number of holes 53 for the reception of a stop-pin 54. By shifting this pin from one hole to another one limit of movement of the controller may be determined with minute accuracy. The features 35 of the feed regulator mechanism as thus far described are well-known but the automatic mechanism now about to be described embodies novel features and improvements forming the subject-matter of 40 the present invention in conjunction with what has already been described.

The stud 55 connecting the controller 50 and the link 51 serves also as a connection with a link comprising two pivotally connected members 56 and 57. These members are connected by a pivot pin 58. The member 57, which is in the form of a rod, extends loosely through a block 60, and is provided with a screw-thread to take nuts 61 and 55 nuts 62. These nuts may be adjusted to various positions so that there will be more or less lost motion between the rod and the swiveled block, as may be required, or they may be adjusted so as to take up all lost motion. It is preferable, however, for some purposes to interpose a compression spring 63 as a cushioning medium between the block 60 and the nuts 62, but this may be omitted without defeating the purpose of 60 the invention.

The block 60 is provided with a stem 64 which is arranged to turn in a bearing in the upper end of an operating lever 65. The lower end of the lever is arranged upon a fulcrum stud 66, and a cam roll 67 carried by 65 the lever occupies a grooved cam 68 mounted upon a stud-shaft 69. This stud-shaft is fixed in a bracket 70 bolted to the main frame 10. A gear 71 is fastened to the cam 68 and is arranged to be driven by a gear 72 carried by the shaft 20. When it is desired to produce alternate long and short feeding steps consistent with the arrangement of the eyelets shown by Fig. 6 the ratio of the gears 72 and 71 will be as 1 to 2, 75 thereby causing the cam 68 to rotate at one-half the speed of the shaft 20. This gear ratio may, of course, be varied to produce a different grouping of the fasteners. The effect of the cam 68 is to shift the controller 80 50 toward the rear during one cycle of the fastener-setting mechanism and to shift it toward the front during the next cycle, each alternate cycle being characterized by a short feeding step while the other cycles are 85 characterized by a long feeding step. The length of the steps may be varied in different ways. For example, the fulcrum stud 66 of the cam lever 65 is adjustable up and down so as to increase or decrease the distance traveled by the upper end of the lever. For this purpose the lower end of the lever is provided with a radial slot 73 through which the stud 66 extends, the stud being adjustably secured to a bracket or 90 other fixture 74 which is provided with a slot corresponding to that mentioned. This adjustment is convenient for producing relatively great changes in the amplitude of 95 feeding motion, but for relatively fine adjustment after the desired amplitude of motion has been approximated it would be more convenient to turn the nuts 61 and 62 so as to afford lost motion as hereinbefore explained. 100

In case the aforesaid adjustments produce a short feeding step that is too short the stop pin 54 may be used to arrest the controller while the cam lever is executing its backward stroke without affecting the length 115 of the longer step. When the pin 54 is used it would arrest adjusting motion in one direction only, and in this case excess motion of the operating lever would be spent in compressing the spring 63. According to 120 the arrangement shown the pin 54 is arranged to determine the length of the shorter step, but if it were desired to use it to determine the length of the longer step it would be placed in front of the controller 125 50 instead of behind it and the cushioning spring 63 would be placed between the swiveled block 60 and the nuts 61 instead of remaining between the block and the nuts 62.

With these three adjusting devices the ma- 130

chine may be adjusted to change the length of the longer feeding step without altering the length of the shorter step, or it may be adjusted to change the length of the shorter step without altering the length of the longer step. It can also be made to change the length of both the longer and shorter steps equally or unequally as desired, thus affording all the possible changes that 10 would be desired and affording fine increments of adjustment in every respect.

Having thus described my invention, what I claim as new and desire to secure by Letters Patent of the United States is:

15 1. A fastener-setting machine comprising automatic fastener-setting mechanism, regulatable work-feeding mechanism arranged to feed an article of work step by step to successive fastener-receiving positions, and 20 automatic means constructed and arranged to regulate said work-feeding mechanism for each fastener to produce long and short spacing alternately with respect to successive fasteners.

25 2. A fastener-setting machine comprising automatic fastener-setting mechanism including a tool for operating on the fasteners, regulatable work-feeding mechanism of which said tool is an element, and automatic means constructed and arranged to regulate said work-feeding mechanism periodically to produce alternate long and short spacing of successive fasteners.

30 3. A fastener-setting machine comprising fastener-setting mechanism, regulatable work-feeding mechanism arranged to feed an article of work step by step to successive fastener-receiving positions and adapted to vary the length of the feeding steps so as 35 to vary the spacing of fasteners, and automatic means constructed and arranged to regulate the work-feeding mechanism once for each cycle of the feeding operation so as 40 to produce two lengths of feeding steps alternately.

45 4. A fastener-setting machine comprising fastener-setting mechanism, regulatable work-feeding mechanism adapted to vary the length of the feeding steps, and automatic means constructed and arranged to regulate the work-feeding mechanism after 50 each cycle of the fastener-setting mechanism to effect alternately long and short spacing of the fasteners, said regulating means being 55 adjustable to vary the difference between the long and short space intervals.

5. A fastener-setting machine comprising a stationary work-table, fastener-setting mechanism, regulatable work-feeding mechanism adapted to feed flat work along 60 said work-table, and automatic means constructed and arranged to regulate the work-feeding mechanism periodically to produce alternate long and short spaces between successive fasteners, said regulating means be-

ing adjustable to vary the length of said spaces.

6. A fastener-setting machine comprising fastener-setting mechanism, regulatable work-feeding mechanism adapted to vary 70 the length of the feeding steps and including a controller movable in one direction to increase and in the opposite direction to decrease the length of step, and mechanism constructed and arranged to reciprocate said controller so as to produce two lengths of 75 feeding steps alternately.

7. A fastener-setting machine comprising fastener-setting mechanism, regulatable work-feeding mechanism adapted to vary 80 the length of the feeding steps and including a controller movable in one direction to increase and in the opposite direction to decrease the length of step, and mechanism 85 constructed and arranged to reciprocate said controller so as to produce two lengths of feeding steps alternately, the latter said mechanism being adjustable to vary the amplitude of regulating motion imparted to 90 said controller.

8. A fastener-setting machine comprising fastener-setting mechanism, regulatable work-feeding mechanism adapted to vary the length of the feeding steps and including a controller movable in one direction to increase and in the opposite direction to decrease the length of step, and mechanism 95 constructed and arranged to reciprocate said controller so as to produce two lengths of feeding steps alternately, the latter said mechanism being adjustable to vary both 100 limits of regulating movement of said controller.

9. A fastener-setting machine comprising fastener-setting mechanism, regulatable work-feeding mechanism adapted to vary 105 the length of the feeding steps and including a controller movable in one direction to increase and in the opposite direction to decrease the length of step, mechanism constructed and arranged to reciprocate the controller so as to produce two lengths of feeding steps alternately, the latter said mechanism being resilient with respect to one 110 direction of regulating motion, and adjustable means arranged to limit the movement of the controller in said direction.

10. A fastener-setting machine comprising fastener-setting mechanism, regulatable work-feeding mechanism adapted to vary the length of the feeding steps and including a controller movable in one direction to increase and in the opposite direction to decrease the length of step, and mechanism 115 constructed and arranged to reciprocate said controller so as to produce two lengths of feeding steps alternately, the latter said mechanism including a reciprocatory actuator, and a link and adjustable couplings arranged to transmit motion from said actu- 120 125 130

- ator to the controller, said couplings being adjustable to provide for lost motion between the actuator and the controller.
11. A fastener-setting machine comprising 5 fastener-setting mechanism, regulatable work-feeding mechanism adapted to vary the length of the feeding steps and including a controller movable in one direction to increase and in the opposite direction to 10 decrease the length of step, and mechanism constructed and arranged to reciprocate said controller so as to produce two lengths of feeding steps alternately, the latter said mechanism including a reciprocatory actuator, resilient means arranged to transmit regulating motion from said actuator to the controller, and adjustable means arranged to limit the regulating movement of the controller.
12. A fastener-setting machine comprising 15 fastener-setting mechanism, regulatable work-feeding mechanism adapted to vary the length of the feeding steps and including a controller movable in one direction to increase and in the opposite direction to 20 decrease the length of step, and mechanism constructed and arranged to reciprocate said controller so as to produce two lengths of feeding steps alternately, the latter said mechanism including a lever, a cam arranged 25 to oscillate the lever, means arranged to transmit regulating motion from the lever to the controller, and an adjustable fulcrum member serving said lever so as to vary its 30 amplitude of angular motion.
13. A fastener-setting machine comprising fastener-setting mechanism including a 35 clenching tool, regulatable work-punching mechanism adapted to punch a hole in the work at various distances from the setting locality, automatic mechanism constructed 40 and arranged to regulate the punching mechanism so that the holes will be punched at different distances from the setting locality, and mechanism arranged to move said 45 clenching tool to feed the work so as to transfer the punched hole from the punching locality to the setting locality.
14. A fastener-setting machine comprising 50 fastener-setting mechanism including a work-feeding and fastener-setting tool, mechanism arranged to punch a hole in the work at various distances from the setting
- locality, regulatable mechanism arranged to operate said tool so as to feed the work by 55 engagement with the edge of the punched hole, and automatic mechanism constructed and arranged to regulate the punching mechanism and the feeding mechanism so that the spacing of the punched holes and 60 the feeding steps will be alternately long and short.
15. A fastener-setting machine comprising fastener-setting mechanism, regulatable work-feeding mechanism, automatic mechanism constructed and arranged to regulate the feeding mechanism so as to produce two lengths of feeding steps alternately, regulatable mechanism for punching a hole 65 in the work to receive the fastener, and means connecting said automatic regulating mechanism with said punching mechanism so that the latter will be automatically controlled to vary the spacing of the punched holes in accordance with the length of the 70 feeding steps.
16. A fastener-setting machine comprising 75 punching mechanism including a tool for punching a hole in the work, a fastener-setting tool arranged to be laterally movable to feed the work to transfer the punched hole from the punching locality to the fastener-setting locality, regulatable mechanism arranged to impart feeding movement to said feeding tool, and means arranged to 80 regulate said feeding mechanism automatically to vary the length of the feeding movements.
17. A machine for operating on shoes, comprising mechanism including a tool arranged to function repeatedly to perform a series of operations on the shoe, said tool being laterally movable to feed the work so as to determine the points at which said operations shall be performed, regulatable 85 mechanism arranged to impart feeding movement to said tool, and mechanism operable automatically to regulate said feeding mechanism to produce alternate long and short spaces between successive points in the 90 work at which said operations are performed.
- In testimony whereof I have signed my name to this specification.

ALBERT E. HUDSON.
